US0D1031461S

(12) **United States Design Patent** (10) **Patent No.:** **US D1,031,461 S**
(45) **Date of Patent:** **** Jun. 18, 2024**

(54) **RADIATION DETECTOR**

(71) Applicant: **Shenzhen Wang An Technology Co., Ltd.**, Shenzhen (CN)

(72) Inventor: **Yingrui Xu**, Shenzhen (CN)

(73) Assignee: **Shenzhen Wang An Technology Co., Ltd.**, Shenzhen (CN)

(**) Term: **15 Years**

(21) Appl. No.: **29/920,526**

(22) Filed: **Dec. 12, 2023**

(51) LOC (14) Cl. **10-04**

(52) U.S. Cl.

USPC **D10/47**

(58) **Field of Classification Search**

Primary Examiner — George D. Kirschbaum

Assistant Examiner — Antoinette Martine Suiter

(57) **CLAIM**

The ornamental design for a radiation detector, as shown and described.

DESCRIPTION

FIG. 1 is a front perspective view of a radiation detector, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the radiation detector, which form no part of the claimed design.

1 Claim, 8 Drawing Sheets
